UNITED STATES PATENT OFFICE.

JAMES D. CLEMMONS, OF HANOVER, INDIANA.

SLATE-CLEANER.

SPECIFICATION forming part of Letters Patent No. 395,121, dated December 25, 1888.

Application filed August 14, 1888. Serial No. 282,705. (No model.)

To all whom it may concern:

Be it known that I, JAMES D. CLEMMONS, a citizen of the United States, residing at Hanover, in the county of Jefferson and State of Indiana, have invented certain new and useful Improvements in Slate-Cleaners; and I do declare the following to be a full, clear, and exact description of the invention, such as will enable others skilled in the art to which it appertains to make and use the same.

This invention has relation to improvements in that class of devices known as "slate and blackboard cleaners," and is designed as an improvement upon those carrying a sponge or absorbent material in a receptacle carrying a valve for feeding the moisture thereto.

The invention will be fully understood from the following description and claim, when taken in connection with the accompanying drawings, in which—

Figure 1 is a side view of my improved device. Fig. 2 is a longitudinal sectional view of the same. Fig. 3 is a cross-sectional view taken on the line $x-x$ of Fig. 2, and Fig. 4 is a detail sectional view of a modification.

Referring by letter to the said drawings, A indicates a tubular receptacle, which is divided by a transverse partition, a , into a sponge-receptacle, b , and a water-receptacle, c , the latter being of a greater capacity than the former, and is provided at its outer end with an aperture, d , designed to be closed by a cork, B , which is secured to the tubular frame or receptacle by means of a cord or the like.

The forward end of the sponge-receptacle is annularly perforated around its mouth to receive securing-threads, as shown, for holding the sponge in position.

C indicates the sponge, which is secured in the receptacle b by threads, so that it may be held away from the valve and allow the latter to move freely, as will be presently described. This sponge-receptacle has an elongated slot, e , for the passage of the valve-rod E , which has one end secured to the transverse parti-

tion a and bears a valve, f , designed to close the aperture g in the said partition. This valve or rod has its outer end bent angularly, and terminates in a thumb or finger portion, h , which may be conveniently manipulated while held in the hands as a pen or pencil.

When the device is not in use, the sponge may be covered by a cap, such as F.

In Fig. 4 of the drawings I have shown a modification of my invention. In this modification, instead of depending upon the resiliency of the rod E , I provide a pivoted valve-rod, G , and form a collar thereon, and between this collar and the inner walls of the sponge-receptacle I surround the said rod with a spiral spring, g' , and from the partition a , I extend a small tube, k , with its outer end vertically exposed to receive the lower end of the valve-rod. This tube communicates with the water-chamber C , and the valve-rod is guided in position by means of an arm, l , having an aperture therein.

Having described my invention, what I claim is—

As an improved article of manufacture, the slate-cleaner herein described, consisting, essentially, of the tubular case having an aperture at one end and a cork for closing the same, and divided by a partition, a , into a water-receptacle, C , and a sponge-receptacle, b , and the said partition having an aperture, g , the sponge-receptacle being slotted at e and perforated at its outer end, as shown, the valve-rod having a finger-piece on its outer end secured at its inner end within the sponge-receptacle and carrying a valve, f , to close the aperture in the said partition, and the sponge sewed in the outer end of the said sponge-receptacle, substantially as specified.

In testimony whereof I affix my signature in presence of two witnesses.

JAS. D. CLEMMONS.
